Attn:

UNITED STATES PATENT OFFICE.

EDWARD HOLBROOK, OF NEW YORK, N. Y.

DESIGN FOR A HANDLE FOR SPOONS, &c.

SPECIFICATION forming part of Design No. 27,847, dated November 16, 1897.

Application filed October 4, 1897. Serial No. 654,093. Term of patent 7 years.

To all whom it may concern:

Be it known that I, EDWARD HOLBROOK, a citizen of the United States, residing at New York, in the county of New York and State of New York, have invented and produced a new and original Design for the Handles of Spoons, Forks, and Similar Articles; and I hereby declare that the following is a full, clear, and exact description of the same, reference being had to the accompanying drawings, forming part thereof.

Figure 1 is a view of the obverse side of the handle showing my design, and Fig. 2 a view of the reverse side of the same.

The leading feature of my design consists in the representation of the stems and leaves of meadow grasses interlaced with the blossoms and leaves of the white clover, arranged in an ornamental pattern on the sides of a handle.

In the drawings, A indicates the stem, and B the blade of the handle. Along the margins of both the obverse and reverse sides of the handle extend the stems 4, from which the leaves 5 extend upward and in easy curves over, under, and across each other, until they terminate near the upper end of the handle in the raised representation of a bunch of white clover, forming the end ornament 6. The leaves of grasses 5 inclose the panel 7 on both sides of the handle. The part 8 of the panel 7, which is plain on the reverse

side, is filled with the representation of a bunch of white-clover blossoms and leaves on the obverse side of the handle. A floral spike 35 9, resembling the spike of the meadow plant known as the "crested dogstail," extends diagonally across the middle of the stem of the handle, inclosed in the leaves of the grasses. On the reverse side this portion of the handle 40 has the space between the leaves of the grasses filled with the representation of the blossoms and leaves of white clover 10, and on the obverse side of the handle the spaces 11 and 12, between the leaves and stems of the 45 grasses, are filled with the representations of the blossoms and leaves of the white clover. The whole presents the appearance of blades and flowers of meadow grasses entwined and inclosing the blossoms and leaves of white 50 clover, *Trifolium ripens perenne*, the stems, leaves, and blossoms being in relief.

Having thus described my invention, what I claim as new, and desire to secure by Letters Patent, is—

The design for a handle for spoons, forks, and similar articles herein shown and described.

In witness whereof I have hereunto set my hand.

EDWARD HOLBROOK.
